UNITED STATES PATENT OFFICE.

JOSEPH J. MOEBS, OF WASHINGTON, DISTRICT OF COLUMBIA, ASSIGNOR OF ONE-HALF
TO CHARLES F. CARUSI, OF WASHINGTON, DISTRICT OF COLUMBIA.

BUILDING CONSTRUCTION.

Application filed January 17, 1925. Serial No. 3,185.

To all whom it may concern:

Be it known that I, JOSEPH J. MOEBS, a citizen of the United States, residing at Washington, District of Columbia, have invented certain new and useful Improvements in Building Construction, of which the following is a specification.

This invention relates to building construction, and more particularly to fireproof building construction.

An object of the invention is a simple and inexpensive method for the construction of fireproof buildings, wherein a frame of reinforced concrete is employed in conjunction with hollow tile walls.

Another object of this invention is the construction of a fireproof building wherein the walls are formed preparatory to the forming of the frame.

Another object of this invention is the construction of a wall, wherein the wall is formed in sections preparatory to pouring the intermediate columns, the wall being constructed in such a manner that the columns interlock with the walls and exert a compression or wedging effect upon the wall sections, regardless of the type of wall construction or material used.

Another object of this invention is to form the flooring and footing in one homogeneous mass without the use of forming material.

Another object of this invention is to form the columns with a flared base designed to more uniformly distribute the load.

Another object of this invention is to construct a building of the reinforced concrete and hollow tile type wherein the construction is a matter of reproducing units; each unit constituting a story.

Another object of this invention is the interlocking of the floor with the wall in such a manner as to form spandrel beams.

Another object of this invention is the formation of the corner columns, the interlocking of the same with the wall and with a veneering so as to form a homogenous mass without disturbing the perfect alignment of the finished wall.

Another object of this invention is the formation of a hollow tile wall in sections floated down or pargeted preparatory to the formation for the columns, which are poured intermediate the wall sections so that their outer surfaces will be in perfect alignment.

Another object of this invention is the

formation of hollow tile walls in sections prior to the formation of the reinforced concrete frame, the formation of the frame being such as to interlock and compress or bind the wall sections in place.

Another object is to have the wall construction carrying part of floor loading rather than the skeleton, which ordinarily carries the walls and floors.

Another object of this invention is the formation of hollow tile walls in sections prior to the formation of the reinforced columns, the arrangement of the walls being such that they are caused to form or provide a part of the form for the columns, thus effecting a great saving in the use of forming material.

A further object of this invention is the building of hollow tile walls and the formation of the frame in units to floor height by employing the minimum amount of forming material which has a repeated usage in that the same material is used for each unit formed.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings forming a part of this specification:

Figure 1 is a side elevation of a section of a building illustrating various methods of arranging tile in the wall sections, with intermediate and interlocking columns, the floor systems being shown in section at various elevations;

Fig. 2 is a horizontal sectional view taken on line 2—2 of Fig. 1, illustrating one of the columns with fragmentary sections of the adjacent wall;

Fig. 3 is an enlarged vertical sectional view taken on the line 3—3 of Fig. 1;

Fig. 4 is an enlarged horizontal sectional view illustrating the application of the forms for casting a column after the exterior wall has been pargeted;

5 Fig. 5 is a perspective of a hollow tile such as employed in the construction of walls and columns in accordance with my invention;

10 Fig. 6 is a side elevation illustrating a column between floors with fragmentary sections of the abutting walls, showing one of the methods of arrangement of the tile so as to increase the base of the column and to produce an interlocking effect between the column and wall sections;

15 Fig. 7 is a like view after the floor has been poured and the forms removed.

Before carrying my invention into actual operation, the ground should first be made level, or substantially so, to a depth equal 20 to that of the thickness of the ground floor slab, after which a trench is excavated in accordance with the outline of the floor plan of the building, and to a predetermined width and depth dependent upon the size, 25 character and number of units employed in the building to be erected, and the nature of the soil upon which the structure is to stand.

In this construction I employ only such 30 materials as are in general use, such as sand, gravel, cement, reinforcing bars and tile. The sand, gravel and cement are mixed in groutings according to various formulas, and the tile employed consists of an ordinary building tile 1 having four cells 2, how- 35 ever, heavier or lighter tile or tile with a less or greater number of cells may be employed.

The preliminary operation having been 40 effected, the actual operation or construction now takes place by filling the excavated trenches and covering the leveled ground enclosed by the trenches with concrete grouting mixed in accordance with any of the well known formulas, thus forming the footing 3 and the ground floor 4 in one homogeneous mass to the ground floor level.

45 Embedded within the footing 3 are horizontal reinforcing bars 5. At location of the columns, vertical reinforcing bars 7, of proper size, project above the ground floor level to a suitable distance to effect a substantial tie between footing 3 and the bases of columns 6 which are subsequently poured. The footings are further reinforced by horizontal bars 8, rods 9 extending at right angles to bars 8, and by bars 10 which conform with the bases of the columns and are subsequently embedded therein.

50 At this stage of the construction, the actual building of the walls takes place. In Fig. 1, I have illustrated the construction of a building comprising three floors above ground level. It is to be understood, of course, that only one unit or a height to one floor level is to be built at a time. This is a 55 very economical method of construction

owing to the repeated usage of the forming material and knock down forms which are of such a character and design that they are equally applicable to the formation of any story unit.

Beginning with the footing 3, and the ground floor 4, which takes the same level, the location of the columns 6 having been determined, by the reinforcing tie rods in the 70 footing provided at such locations, as previously described, the width of the columns is then laid off over the footings in accordance with the floor plan. The tile is then set in wall sections in the spaces between the 75 spaces laid off for the columns. In the laying or setting of the tile sections of the first unit, the first two and the last two tiles 11 are laid on their sides, or horizontally, with the intermediate tile 12 perpendicular, the 80 object of which will hereinafter appear.

All of the tile 11 and 12 are set to form 85 the complete sections of the wall of the first unit; the usual cement mortar is employed for this purpose, the wall being floated down or pargeted with laying up of the walls, as at 13, most clearly shown in Figs. 2, 4, and 7. Pargeting is an economical 90 method of erecting walls for certain types of buildings. In some cases the outer walls are not pargeted, but the outer walls may be stuccoed or otherwise covered upon completion of the walls. This step in the construction having been accomplished, the 95 knock-down forms for constructing the columns are then assembled in place.

100 After the column forms have been arranged and adjusted, the column reinforcing rods 31 being in position, the floor forming is then placed in position, using heavy material for this purpose. In case there is an intersecting beam, such as is shown at 33 in Fig. 1, these, of course, must be allowed for in placing the floor forming. The next step is the forming or casting of the columns, 105 which is accomplished by pouring cement grouting of a consistency sufficiently soft to admit of a flow, the object being to fill the space enclosed by the adjacent ends of the wall sections and the column forms, and at the same time fill as near as possible the 110 tile cells of the horizontally set tile 11, thus producing a column which has a thickness equal to the thickness of the wall, and a breadth equal to the space between the wall sections plus the width of the horizontally set tile.

115 Said columns 6 as designated by 25 on the first floor (see Fig. 1) have a flared portion 24.

120 This form of column is applicable to the various units except that the quantity of horizontally set tile varies as the height of the building progresses, as for example, the unit between the first and second floors 125 wherein one and one-half tiles are set hori-

zontally, as at 34, on each side of the column; and again between the second and third floors in the construction of the third unit, wherein one tile is set horizontally, as at 35, one on each side of the column. Again, as shown in Fig. 1, the tiles may all be set with their cells vertical and then none of the column material finds its way into the tile cells. The columns thus formed interlock with the tile sections, and, by virtue of their close contact therewith, exert a compression or binding force between the tile in the various wall sections.

It is to be noted that the last row of tile in the wall section is set horizontally, as shown at 41, and that adequate reinforcing bars 42 are distributed over the same. It is also to be understood that the flooring is provided with more or less reinforcing bars, depending upon the span and the load which the floor is to carry.

The floor 43 is now poured in the usual manner, and after setting or hardening, all the forms are stripped away, the clamping bolts being cut off in the wall, thus producing a complete unit. It is to be observed that the floor thus formed can and does act either as a floor for the next succeeding unit, or a roof for the completed unit, and that the floor or roof thus formed, by virtue of its bearing over the entire thickness of the wall, as shown at 42', exerts a binding force between the tiles and acts as a spandrel beam, thus effecting an enormous saving in cost of production.

In Fig. 6 I have illustrated wall sections laid up or set with alternating horizontally set tile, as shown at 43', which demonstrates the various methods of interlocking the columns and jambs.

In Fig. 7 I have shown a modified form of wall and floor construction, wherein the upper course of tile are set horizontally with their upper cells broken away, as shown at 50, in order to form a beam 51 integral with the floor 43. In such cases reinforcing bars 52 are inserted in the tile cells. The tile cells are filled with the laying of the floor.

This form of beam and floor is very desirable in that no forming material whatsoever is required for producing the beam, which is embedded in and forms a part of the wall construction, and again a beam thus formed serves as a better binder for the wall sections and tends to tie in the floor by reason of the fact that it becomes an integral part thereof.

While I have shown and described the preferred embodiment of my invention, I wish it to be understood that I do not confine myself to the precise details of construction herein set forth, by way of illustration, as it is apparent that many changes and variations may be made therein, by

those skilled in the art, without departing from the spirit of the invention, or exceeding the scope of the appended claims.

Having thus described the various features of my invention what I claim as new, and desire to secure by Letters Patent is:

1. A wall construction composed of spaced tile wall sections laid in courses, mainly of vertically set tile, the outermost tile of some courses set horizontally, cementitious columns intermediate the wall sections and keyed thereto by the material of said columns entering into the cells of the horizontally set tiles. 75

2. A wall construction composed of spaced tile wall sections laid in courses, mainly of vertically set tile, more than one tile at the ends of each course set horizontally, cementitious columns intermediate the wall sections and keyed thereto by the material of said columns entering into the cells of the horizontally set tiles. 85

3. A wall construction composed of spaced tile wall sections laid in courses, the outermost tile of some courses set horizontally, cementitious columns intermediate the wall sections and keyed thereto by the material of said columns entering into the cells of the horizontally set tiles. 90

4. A wall construction composed of spaced tile wall sections laid in courses, more than one tile at the ends of some courses set horizontally, cementitious columns intermediate the wall sections and keyed thereto by the material of said columns entering into the cells of the horizontally set tiles. 95

5. In building construction, tile wall sections, intermediate and interlocking columns, cementitious floor beams, cementitious floor sections integral with the beams, and beams integral with the floor formed in the tile walls and extending parallel to the wall construction. 105

6. In building construction, a cement flooring, a cement footing integrally formed with the flooring, wall sections, cement columns intermediate the wall sections and binding therewith, and flared cement sections joining the columns and the footing and integrally formed therewith to tend to prevent overturning of the footing. 110

7. In building construction, a lower cement flooring, a cement footing integrally formed with the lower flooring, wall sections, cement columns intermediate the wall sections and binding therewith, upper cement flooring binding the columns and the walls, and flared cement sections joining the columns and the footing and integrally formed therewith to tend to prevent overturning of the footing. 120

8. A building construction comprising hollow tile wall sections laid in courses, the outermost tile of some courses set horizontally, cementitious columns intermediate 125

the wall sections and keyed thereto by the material of said columns entering into the cells of the horizontally set tiles, a cementitious floor having a direct bearing and binding force on the wall and the columns, and reinforcing material in the columns and floor.

9. A building construction comprising hollow tile wall sections laid in courses, the

outermost tile of some courses set horizontally, cementitious columns intermediate the wall sections and keyed thereto by the material of said column entering into the cells of the horizontally set tiles, and cementitious floor sections bearing against and interlocking with the wall sections and the columns.

In testimony whereof I affix my signature,

JOSEPH J. MOEBS.
